US0D1105153S

(12) **United States Design Patent** (10) **Patent No.:** **US D1,105,153 S**
(45) **Date of Patent:** **** Dec. 9, 2025**

(54) **DISPLAY SCREEN OR PORTION THEREOF
WITH GRAPHICAL USER INTERFACE**

- (71) Applicant: **Apple Inc.**, Cupertino, CA (US)
(72) Inventors: **Tiffany Jon**, Sunnyvale, CA (US);
Stephen O. Lemay, Palo Alto, CA (US)
(73) Assignee: **Apple Inc.**, Cupertino, CA (US)
(**) Term: **15 Years**
(21) Appl. No.: **29/972,029**
(22) Filed: **Nov. 7, 2024**

Related U.S. Application Data

- (63) Continuation of application No. 29/855,044, filed on Sep. 29, 2022, now Pat. No. Des. 1,051,162, which is a continuation of application No. 29/778,883, filed on Apr. 15, 2021, now abandoned, which is a continuation of application No. 29/676,738, filed on Jan. 14, 2019, now Pat. No. Des. 916,732, which is a continuation of application No. 29/606,395, filed on Jun. 5, 2017, now Pat. No. Des. 842,877.

(57) **CLAIM**

The ornamental design for a display screen or portion thereof with graphical user interface as shown and described.

DESCRIPTION

The sole FIGURE shows a display screen or portion thereof with graphical user interface showing our new design. The peripheral dashed broken lines illustrate a display screen or portion thereof, and form no part of the claimed design.

1 Claim, 1 Drawing Sheet
